UNITED STATES PATENT OFFICE

SEBASTIANO CONTE, OF PRINCETON, NEW JERSEY

COMBINED CLOTHESLINE REEL, ROPE WASHER, AND BRUSH

Application filed March 14, 1930. Serial No. 435,910.

This invention relates to certain new and useful improvements in combined clothes line reel, rope washer and brush.

The primary object of the invention is to provide a clothes line reel, wherein a clothes line moves over guide pulleys in an endless path with the guide pulleys at one end of the line enclosed in a casing having a water filling spout and a valve controlled outlet with rotary brush elements journaled in the casing for the washing and brushing of a clothes line rope.

With the above and other objects in view that will become apparent as the nature of the invention is better understood, the same consists in the novel form, combination and arrangement of parts hereinafter more fully described, shown in the accompanying drawings and claimed.

20 In the drawings:—

Figure 1 is a fragmentary top plan view of a clothes line reel, rope, washer and brush constructed in accordance with the present invention.

25 Figure 2 is a fragmentary side elevational view showing the endless clothes line passing over guide pulleys with one of the pulleys located in a casing containing the brush members;

30 Figure 3 is an edge elevational view of the casing containing one of the guide pulleys showing the side outlet opening therefrom;

Figure 4 is a horizontal sectional view taken upon line 4—4 of Figure 2 showing 35 the guide pulley journaled in the casing;

Figure 5 is a horizontal sectional view taken on line 5—5 of Figure 2;

Figure 6 is a vertical cross-sectional view taken on line 6—6 of Figure 3 showing the 40 rotatable brush members having gear connections with the guide pulley in the casing;

Figure 7 is an enlarged detail sectional view showing the large central brush member with its bearing and drive gear;

45 Figure 8 is a side elevational view of the drive gear and brush bearings shown in Figure 7;

Figure 9 is a side elevational view of the brush member associated with the bearings 50 shown in Figure 8;

Figure 10 is a side elevational view of a bearing member and drive gear for a smaller brush member; and

Figure 11 is a side elevational view of the brush member associated with the bearing 55 shown in Figure 10.

Referring more in detail to the accompanying drawings, there is illustrated a combined clothes line reel, rope washer and brush, the clothes line rope 1 being endless and passing 60 over guide pulleys 2 and 3, the guide pulley 3 being carried by a support 4 having an end hook 5 adapted for attachment to a suitable support, while the guide pulley 2 is journaled in a casing 6 that carries a hook 7 for 65 attachment to a support.

The casing 6 is of the general design shown in side elevation in Figures 2 and 6, and embodies side walls 8 connected by edge walls 9 and 10, the upper side of the edge wall 10 70 being cut away to provide an opening 11 for the passage of the rope 1. The upper side of the edge wall 9 carries a funnel or spout 12 while the lower side of the edge wall is provided with an outlet nozzle 13 closed by 75 a removable plug 14. It is intended to partially fill the casing 6 with water through the filling spout 6 for the washing of the rope 1 in its endless travel through the casing and said water is discharged through the spout 80 13 upon removal of the plug 14.

Guide pulley 2 has central radial bearing studs 15 terminating adjacent the inner faces of the side walls 8 with bearing screws 16 85 rotatable in openings in the side walls entering the bearing studs 15 for rotatably supporting the pulley 2 as will at once be evident from an inspection of Figure 4. A pair of guide pulleys 17 are similarly journaled between the side walls 8 in spaced relation to 90 each other adjacent the opening 11 and over which the rope 1 passes as illustrated in the several figures, the guide pulleys 17 also comprising the bearing screws 17a.

As shown in Figures 6 and 7, a relatively 95 large cylindrical brush 18 has a keyed hub portion 19 keyed on the bearing 20 that has formed integral with one end thereof a relatively large gear wheel 21. The opposite ends of the bearing 20 have threaded sockets 100

to receive the bearing screws 22 having outer cylindrical ends journaled in openings in a side wall 8 and a removable door 8a of the casing for securing the brush 18 in position between the spaced sections of the rope 1 as shown in Figure 6 and between the guide pulleys 2 and 17, the brush 18 having the bristles or fibres thereof engaged with the rope 1 as illustrated.

10 A smaller brush 23 having a keyed hub 24 is received on the key bearing 25, similar to the bearing 20, the bearing 25 having a pinion 26 preferably formed integral at one end thereof, opposite ends of the key bearing 25 having threaded sockets to receive bearing screws 27 journaled in a side wall 8 and the door 8a of the casing for supporting the brush 23 at opposite sides of the brush 18 and in a position for engagement with the outer sides 20 of the spaced lengths of the rope 1. The guide pulley 2 carries a facial gear 28 formed integral therewith that meshes with the gear 21 upon the key bearings 25, the gear 21 meshing with the gears 26 upon the key bearing 25. The side door 8a as shown in Figs. 2 and 7 is retained in position by the screws 7b, the door being removable to permit lateral displacement of the brush elements for renewal or repair.

20 The clothes line is operatively mounted by engaging the hook 5 upon the dash board support 4 and the hook 7 upon the casing 6 on suitably spaced supports with the rope 1 extended in a taut condition. The rope 1 is 25 drawn into and out of the casing 6 by a pull upon one section thereof and in this travel, the rope is engaged by the brushes 18 and 23 for cleaning the same and presenting a clean stretch of rope for the support of clothes to 30 prevent soiling thereof. It is also intended to wash the rope by partially filling the casing 6 with water through the filling spout 12 and upon drawing the rope into and out of the casing 6, the same becomes saturated traveling through the water and scrubbed by the brushes 18 and 23. The water is discharged from the casing 6 through the outlet nozzle 13. The guide pulley 2 with the gear 28 carried thereby forms the motive means for the 35 brush members as will at once be evident from an inspection of Figure 6, to effect a thorough cleaning of the rope 1 and for maintaining the same in such condition.

While there is herein shown and described 40 the preferred embodiment of the invention, it is nevertheless to be understood that minor changes may be made therein without departing from the spirit and scope of the invention as claimed.

60 I claim:—

1. A device for use with an endless clothes line comprising a casing in which a pulley is journaled and about which a clothes line is adapted to be trained, rotary brush members journaled in the casing in wiping contact

with the runs of the clothes line, and operative connections between the brush members and the pulley to effect rotation of the brush members upon rotation of the pulley.

2. A device for use with an endless clothes line comprising a casing in which a pulley is journaled and about which a clothes line is adapted to be trained, rotary brush members journaled in the casing in wiping contact with the runs of the clothes line, operative connections between the brush members and the pulley to effect rotation of the brush members upon rotation of the pulley, the casing having a side outlet for the passage of the clothes line and water filling, and discharging means on the casing.

3. A device for use with an endless clothes line comprising a casing in which a pulley is journaled and about which a clothes line is adapted to be trained, rotary brush members journaled in the casing in wiping contact with the runs of the clothes line, and operative connections between the brush members and the pulley to effect rotation of the brush members upon rotation of the pulley, one of said brush members being positioned between the runs of the clothes line and the other brush member disposed at the outer sides of the runs of the clothes line opposite the intermediately positioned brush.

4. A device for use with an endless clothes line comprising a casing in which a pulley is journaled and about which a clothes line is adapted to be trained, rotary brush members journaled in the casing in wiping contact with the runs of the clothes line, operative connections between the brush members and the pulley to effect rotation of the brush members upon rotation of the pulley, the casing having a side outlet for the passage of the clothes line and water filling, and discharging means on the casing, one of said brush members being positioned between the runs of the clothes line and the other brush members disposed at the outer sides of the runs of the clothes line opposite the intermediately positioned brush.

5. A device for use with an endless clothes line comprising a casing in which a pulley is journaled and about which a clothes line is adapted to be trained, rotary brush members journaled in the casing in wiping contact with the runs of the clothes line, and operative connections between the brush members and the pulley to effect rotation of the brush members upon rotation of the pulley, the operative connections between the brush member and pulley including a gear on the pulley meshing with gears on the brush members, a bearing for each brush member journaled in the side walls of the casing with the associated gear integral therewith.

6. A device for use with an endless clothes line comprising a casing in which a pulley is journaled and about which a clothes line

is adapted to be trained, rotary brush members journalled in the casing in wiping contact with the runs of the clothes line, operative connections between the brush members and the pulley to effect rotation of the brush members upon rotation of the pulley, the casing having a side outlet for the passage of the clothes line and water filling and discharging means on the casing, the operative connections between the brush member and pulley including a gear on the pulley meshing with gears on the brush members, a bearing for each brush member journalled in the side walls of the casing with the associated gear integral therewith.

7. A device for use with an endless clothes line comprising a casing in which a pulley is journalled and about which a clothes line is adapted to be trained, rotary brush members journalled in the casing in wiping contact with the runs of the clothes line, and operative connections between the brush members and the pulley to effect rotation of the brush members upon rotation of the pulley, one of said brush members being positioned between the runs of the clothes line and the other brush member disposed at the outer sides of the runs of the clothes line opposite the intermediately positioned brush, the operative connections between the brush member and pulley including a gear on the pulley meshing with gears on the brush members, a bearing for each brush member journalled in the side walls of the casing with the associated gear integral therewith.

8. A device for use with an endless clothes line comprising a casing in which a pulley is journalled and about which a clothes line is adapted to be trained, rotary brush members journalled in the casing in wiping contact with the runs of the clothes line, operative connections between the brush members and the pulley to effect rotation of the brush members upon rotation of the pulley, the casing having a side outlet for the passage of the clothes line and water filling, and discharging means on the casing, one of said brush members being positioned between the runs of the clothes line and the other brush members disposed at the outer sides of the runs of the clothes line opposite the intermediately positioned brush, the operative connections between the brush members and pulley including a gear on the pulley meshing with gears on the brush members, a bearing for each brush member journalled in the side walls of the casing with the associated gear integral therewith.

9. A device for use with an endless clothes line comprising a casing in which a pulley is journalled and about which a clothes line is adapted to be trained, rotary brush members journalled in the casing in wiping contact with the runs of the clothes line, operative connections between the brush members

and the pulley to effect rotation of the brush members upon rotation of the pulley, the casing having a side outlet for the passage of the clothes line and water filling and discharging means on the casing, and a pair of guide spacer pulleys for the runs of the clothes line journalled in the casing adjacent the side outlet.

10. A device for use with an endless clothes line comprising a casing in which a pulley is journalled and about which a clothes line is adapted to be trained, rotary brush members journalled in the casing in wiping contact with the runs of the clothes line, operative connections between the brush members and the pulley to effect rotation of the brush members upon rotation of the pulley, and a side door removably mounted in the casing to permit removal of the brush member with corresponding ends of the brush members journalled in the door.

In testimony whereof I affix my signature.
SEBASTIANO CONTE.
